UNITED STATES PATENT OFFICE.

ORVILLE R. BETTS, OF SAN PEDRO, CALIFORNIA.

COMBINED TOWEL RACK AND CLOTHESLINE.

Application filed May 25, 1926. Serial No. 111,672.

My invention is a combined towel rack and clothes line.

An object of my invention is to form a towel rack structure which may be utilized 5 to house a clothes line of the extensible type, whereby the clothes line may be unreeled through the towel rack and stretched along a wall or the like for hanging clothes.

Another object of my invention is to form 10 the towel rack of tubing so that a clothes line may be reeled on the drum, the line extending through the tubing with the free end of the line retained at the extreme end of the tubing, such line being extensible and 15 fastened to a hook or the like forming a clothes line.

Another object of my invention is to form 20 the housing for the reels with a device forming a brake so that when a line is drawn out the braking device may be applied, thereby preventing the spring from winding in the line.

My invention will be more readily understood from the following description and 25 drawings, in which:

Figure 1 is a perspective view of my towel rack and extensible clothes line, attached to a wall, with one of the lines drawn out;

Fig. 2 is a horizontal section on the line 30 2-2 of Fig. 1 through the towel rack and reeling device;

Fig. 3 is an elevation partly broken away, showing the reeling drum;

Fig. 4 is a vertical section illustrating a 35 section through the spring of one of the reels;

Fig. 5 is a section on the line 5-5 of Fig. 3, through the reels and their housing;

Fig. 6 is a section on the line 6-6 of Fig. 40 3, showing a suitable supporting bracket.

The towel rack structure is constructed substantially as follows:

Suitable brackets 1 are utilized to support the tubes 2, the brackets being attached to 45 the wall 3. These tubes merge into or are attached to a reel housing 4 for the clothes line. This housing at the back preferably abuts against the wall and if desired may be secured thereto. However, the brackets 50 are intended to be sufficiently strong to support the whole device.

It will be noted that the tubes are preferably parallel sided and adjoining the housing they are in alinement as indicated in 55 Fig. 2, being large enough to accommodate the line as it is reeled in and out as here-

under described. In elevation the tubes preferably have parallel sides as indicated by the numeral 7 in Fig. 3. Ornamental knobs 8 with apertures 9 thereon form the 60 ends of the towel rack, it being understood that towels may be hung over the tubes as indicated in Fig. 1.

The mounting for the reels is substantially 65 as follows:

As illustrated, the housing 4 has a rear, preferably circular section 10 which clears the wall. The side walls 11 are preferably cylindrical, being open at the front and having a movable closure plate 12. A round 70 shaft 13 is secured in the housing, being preferably riveted or secured in any other suitable manner to the rear wall so as to be immovable and non-rotatable. Winding reels 15, of which there are two, are loosely 75 mounted on the shaft; each of these reels having a drum section 16 and an actuating spring 17. This spring is suitably secured to the shaft and to the drum.

It will be noted by reference to Figs. 3 80 and 4 that the springs of the inner and outer drums are reversed so that each has a tendency to wind in opposite directions. The free end of the shaft 13 is screw threaded as indicated by 18, having a nut 19 thereon 85 with an operating handle 20.

The clothes line 21 is wound on the drums, there being two clothes lines with their ends secured in any suitable manner to the drums. The lines extend through the 90 tubes 2 and are drawn out of apertures 9 preferably having rings 22 on the end which prevent there being drawn backwardly into the tubes. Hooks 23 or the like, may be 95 secured to a wall so that when the lines are drawn out they may be hooked as shown in Fig. 1 and utilized for hanging clothes or the like.

The manner of operation of my combined 100 towel rack and clothes line is believed obvious. However, it may be stated that the tension of the springs will preferably be sufficient so that the lines will be drawn in and maintained taut. Should a person for any reason wish to draw out a line and to relieve the constant inward tension, it is only necessary to turn the handle and screw the nut 19 tightly on the shaft 13. This action 105 presses the plate 12 against the reels, thus pressing the innermost reel against the back 110 of the housing. This action creates sufficient friction to prevent reeling in or turn-

ing out of the line. Thus a person may obtain a slack line should such be desired.

Such changes may be made as fall within the spirit of my invention as set forth in the 5 description, drawings and claims.

Having described my invention, what I claim is:

- 10 1. A combined towel rack and clothes line comprising a housing having a reel therein, a tube connected to the reel housing and having communication therewith, a clothes line extending through the tube and wound upon the reel, and means to support the housing and the tube on a wall or the like.
- 15 2. A combined towel rack and clothes line comprising in combination a housing, a tube connected thereto, a fixed shaft in the housing, a reel on said shaft, a line extending through the tube and wound on the reel, a loose plate in the housing adjacent the reel, and means operatively connected to the shaft to press said plate against the reel, creating a friction whereby the line may be held unreeled in any desired position.
- 20 3. In a device of the character described, a pair of tubes having an enlarged housing between the same, a pair of reels mounted in

said housing, lines extending through the tubes and wound on the reels, and means to support the tubes spaced from a wall or the like, said tubes forming a towel rack on each side of the housing.

- 25 4. In a device of the character described, a central housing having a plurality of reels, each reel having a drum and a spring, the springs being tensioned to rotate the drums in opposite directions, tubes connected to the housing and extending in opposite directions, lines through the tubes attached to the drums, means to support the tubes on a wall or the like, and spaced therefrom, said tubes forming a towel rack on each side of the housing, the housing having a shaft, the reels being rotatable on said shaft, a loose plate on the shaft, a nut threaded on the shaft bearing against the plate, and means to operate the nut to frictionally press the reels together and against the back of the housing, thereby preventing rotation of same.

In testimony whereof I have signed my name to this specification.

ORVILLE R. BETTS.
